(57) **CLAIM**

The ornamental design for a phone holder as shown and described.

DESCRIPTION

FIG. 1 is a perspective view of a first component of a phone holder shown separately for ease of illustration where two mounting base disposed on two sides of the first component are rotated to a first position;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is another perspective view of the first component of the phone holder where the two mounting bases of the first component are rotated to the first position;

FIG. 10 is a perspective view of the first component of the phone holder where the two mounting bases of the first component are rotated to a second position;

FIG. 11 is a perspective view of a second component of the phone holder shown separately for ease of illustration where a base of the second component is rotated to a first position;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

(Continued)

FIG. 19 is a perspective view of the second component of the phone holder where the second component is rotated to a second position;

FIG. 20 is a perspective view of the phone holder where the phone holder is in a first configuration of use; and, FIG. 21 is a perspective view of the phone holder where the phone holder is in a second configuration of use.

The broken lines in the drawings depict portions of the article that form no part of the claimed design.
